DESIGN FOR A TEXTILE FABRIC

Samuel E. Staines, Allendale, N. J., assignor to
Botany Worsted Mills, Passaic, N. J., a corpora-
tion of New Jersey

Application November 10, 1938, Serial No. 80,997

Term of patent 14 years

To all whom it may concern:

Be it known that I, Samuel E. Staines, a citizen
of the United States, residing at Elmwood Ave-
nue, Allendale, in the county of Bergen and State
of New Jersey, have invented a new, original,
and ornamental Design for Textile Fabrics, of
which the following is a specification, reference
being had to the accompanying drawing, forming
part thereof.

The figure of the drawing is a plan view of a
piece of textile fabric showing my design.

I claim:

The ornamental design for a textile fabric, as
shown.

SAMUEL E. STAINES.
